UNITED STATES PATENT OFFICE.

ALVIN DINGS, OF MILWAUKEE, WISCONSIN, ASSIGNOR OF ONE-HALF TO DAVID DINGS, OF SAME PLACE, AND ALFRED PEW, OF WASHINGTON, DISTRICT OF COLUMBIA.

MAGNETIC SEPARATOR.

SPECIFICATION forming part of Letters Patent No. 628,078, dated July 4, 1899.

Application filed April 20, 1899. Serial No. 713,778. (No model.)

To all whom it may concern:

Be it known that I, ALVIN DINGS, a citizen of the United States, residing at Milwaukee, in the county of Milwaukee and State of Wisconsin, have invented certain new and useful Improvements in Magnetic Separators; and I do hereby declare the following to be a full, clear, and exact description of the invention, such as will enable others skilled in the art to which it appertains to make and use the same.

My invention is an improvement in magnetic separating apparatus; and it consists in the novel features hereinafter described, reference being had to the accompanying drawings, which illustrate one form in which I have contemplated embodying my invention, and said invention is fully disclosed in the following description and claims.

Referring to the said drawings, Figure 1 represents a side elevation, partly in section, of an apparatus embodying my invention. Fig. 2 represents a horizontal section of the same on line 2 2 of Fig. 1. Fig. 3 is an enlarged view of a part of the rotating separating-disk, showing the course of electric current diagrammatically.

A represents a rectangular frame which supports the various parts of the apparatus and which is preferably made of wood.

B is a conveyer consisting in this instance of an inclined longitudinally-reciprocating shallow trough or shaker provided with shallow sides b and an end piece b'. The trough or shaker B is supported from the frame A by hangers b² b² of any preferred construction permitting the longitudinal movement.

C represents the driving-shaft, mounted in bearings secured to the frame and provided with an eccentric c, eccentric-strap c', and eccentric-rod c², which is secured to the trough for imparting a reciprocating movement thereto. The trough or shaker is preferably supported in an inclined position, as shown, and adjacent to its upper end I provide a hopper D, secured to the frame and having at its lower end, immediately above the conveyer, a stirring-roller E, consisting of a shaft mounted in the hopper and provided with pins or projections e. The shaft of the stirring-roller

is provided, outside the hopper, with a driving-pulley e' for operating the stirrer.

F represents a vertically-disposed shaft mounted in suitable bearings f f in the frame and arranged perpendicular to the conveyer B. This shaft is provided with a bevel-gear f', meshing with a bevel-pinion g on a horizontal counter-shaft G, also mounted in bearings secured to the frame A and provided with a band-pulley g', to which motion is imparted by a belt from a pulley c³ on the driving-shaft C. The shaft F is provided with a horizontally-disposed disk or plate H, preferably formed of wood or other non-conducting material, arranged parallel to the conveyer and having a portion overhanging the same and a portion extending laterally beyond the edge of the conveyer, as shown. This disk H is provided with a series of electromagnets I, preferably arranged in a circle around the disk H, as indicated in Figs. 2 and 3, by poles 70 of the magnets extending to or below the lower face of the disk, so that as the disk revolves the poles pass over the conveyer and very close to the same.

I provide means for supplying an electric current to the magnets while they are above the conveyer, certain of the magnets at one side of the conveyer being cut out of the circuit, so that as the disk revolves the magnets will attract metallic particles while passing over the conveyer and will carry them laterally out of line with the conveyer, when they will be cut out of circuit and will drop the metallic particles, which fall into a suitable receptacle. In this instance I have shown 85 the magnets arranged in pairs and the disk H, provided with a circuit-breaker for each pair of magnets, constructed in the following manner, and, as all the circuit-breakers are identical in form, I will describe but one of 90 them.

The disk H is provided with a stationary contact K, preferably in a radial line therewith, which is connected to one magnet of the pair by wire 1, the two magnets of each pair 95 being connected by wires 2 2.

K' represents the movable contact, pivoted on a pin or stud k to the disk and having its

free end adapted to engage the stationary contact K. The movable contact K' is provided with an arm k', extending at an angle thereto, and the portion of the arm K' adjacent to the pivot-pin k is provided with a shoulder k².

K² represents an operating-arm pivoted upon the stud k independently of the movable contact and provided with a friction-roller k³ at its outer end and with a lug or projection k⁴ adjacent to the pivot pin or stud adapted to engage the shoulder k². The arm K² is connected to the arm k' of the movable contact by a yielding connection, in this instance a coiled spring k⁵, and a second spring k⁶ connects the arm K² with a stationary pin, in this instance secured to an arm k⁷, which is rigidly secured to the pivot-pin k and is incapable of movement with respect to the disk.

From the foregoing description it will be seen that the tension of spring k⁶, drawing on arm K² and in turn drawing on arm k' through spring k⁵, will normally hold the movable contact K' in engagement with the fixed contact K. A wire 3 connects one magnet of each pair to the pivot-pin k of its respective switch or contact-breaker.

L represents a curved bar, preferably formed of wood or other non-conducting material, concentric with the axis of disk H and secured to the frame A by brackets l l, so as to be in position to be engaged on its inner face by the friction-rolls k³ of the circuit-breakers. This bar is provided at each end with metallic conducting-strips l l², provided with binding-posts l³ l⁴, respectively, said strips extending along the inner face of the bar, as shown in Fig. 3. The bar L is also provided at each end (preferably near the inner ends of the said contact-strips) with a cam-grade l⁵, the central portion of the bar being nearer the axis of the disk than the end portions. As the disk is revolved the friction-roller of each circuit-breaker will be brought into engagement with the metal contact piece or strip l² and will take current therefrom, as herein-after described. As the roller passes along the strip it will roll up the cam-grade l⁵, thereby moving the operating-arm K² of the circuit-breaker inward, forcing the lug k⁴ thereof into contact with the shoulder k² on the movable contact K' and moving the latter away from its fixed contact K, thus breaking the circuit. The roller then passes along the central non-conducting portion of bar L and is insulated from both of the contact-strips l l² until it passes onto strip l¹ and rolls down the cam-grade l⁵ at the other end of the bar L and allows the spring k⁶ to bring the movable contact again into engagement with its fixed contact. The course of the current is indicated somewhat diagrammatically in Fig. 3, in which but half of the disk H is shown.

M represents the battery or other source of electrical energy, from which the current passes over wire 4 to binding-post l⁴, thence to contact-strip l¹, thence through the friction-roller k³ and arm K² of one of the circuit-breakers (indicated by X on Fig. 3) to its pivot-pin k, thence on wire 3 to one of the magnets of the pair connected with said circuit-breaker, thence on wire 2 to the other magnet, thence on wire 1 to the fixed contact K of the next circuit-breaker to the right, thence through the movable contact K' there- 70 of to its pivot-pin, thence to one of the magnets, and so on around the portion of the disk which overhangs the conveyer to the circuit-breaker (indicated by Y, Fig. 3) whose friction-roll is in engagement with the contact-strip l¹, through said circuit-breaker to the said contact-strip, and over wire 5 from binding-post l³ to the battery M. It will be seen that all of the circuit-breakers lying between X and Y have their friction-rolls engaging 80 the portion of the bar L between the cam-grades l l², and the said circuit-breakers are therefore open and the magnets connected therewith are cut out of the circuit temporarily. I do not wish to limit myself to the use 85 of this form of circuit-breaker.

In order to prevent any metallic particles from adhering to the poles of the magnets while they are cut out of circuit, I prefer to arrange a brush N, secured to a support n, 95 attached to the frame, which brush sweeps the under side of disk H and will positively brush off any particles which might have a tendency to adhere. The material dropped by the magnets falls into a box O or other 100 suitable receptacle.

The driving-shaft is provided with a band-pulley c⁴, by means of which the machine can be driven from any suitable source of power.

In operation the material is fed into the 105 hopper and the machine is placed in motion. The material will fall gradually upon the conveyer—in this instance the shaker—and be moved longitudinally thereof toward its lower end, passing beneath the disk H. As the 110 disk revolves over the material the metallic particles thereof will be picked up by the magnets, carried laterally out of line with the conveyer, and dropped or brushed off, as here- 115 tofore described.

What I claim, and desire to secure by Letters Patent, is—

1. In a magnetic separator, the combination with a conveyer, of a revoluble horizontally-disposed disk lying parallel with said conveyer and having a portion overhanging the conveyer and a portion extending laterally thereof, a series of magnets carried by said disk, circuit-controllers for said magnets carried by said disk and provided each with a 120 stationary and a movable part adapted to make contact with each other, and a stationary device for engaging said movable parts of the circuit-controllers for separating the movable and stationary contacts and cutting 125 said magnets out of circuit while they are out of line with the conveyer, substantially as described.

2. In a magnetic separator, the combina-

tion with a conveyer, of a revoluble horizontally-disposed disk lying parallel with said conveyer and having a portion overhanging the conveyer and a portion extending laterally thereof, a series of magnets carried by said disk circuit-controllers for said magnets carried by said disk and provided each with a movable part and a stationary bar provided with contact-strips in the path of said movable parts of the circuit-controllers, insulated from each other adapted to be connected with the source of electricity, and cam portions on said bar for operating said movable parts of the circuit-controllers for cutting the magnets out of circuit when they are out of line with the conveyer, substantially as described.

3. In a magnetic separator, the combination with a conveyer, of a horizontally-disposed revoluble disk having a portion overhanging said conveyer and a part extending laterally beyond the same, a series of magnets carried by the said disk, a series of circuit-controllers on said disk connected with said magnets, each comprising a fixed and a movable contact and an operating-arm for said movable contact, a stationary bar, located at one side of the conveyer provided with a cam-grade for engaging the said operating-arms of said circuit-controllers for cutting said magnets out of circuit while they are out of line with the conveyer, substantially as described.

4. In a magnetic separator, the combination with a conveyer, of a horizontally-disposed revoluble disk having a portion overhanging said conveyer and a part extending

laterally beyond the same, a series of magnets carried by the said disk, a series of circuit-controllers on said disk connected with said magnets, each comprising a fixed and a movable contact and an operating-arm for said movable contact, a stationary bar located at one side of the conveyer, provided with contact-strips, in the path of said operating-arms, insulated from each other and adapted to be connected with a source of electricity, said bar having cam portions for engaging said arms to separate the movable and fixed contacts, and cut the magnets out of circuit, substantially as described.

5. In a magnetic separator, the combination with an inclined trough, and a hopper adjacent to the higher end thereof, of a horizontal rotary disk having a part extending over said trough, a series of magnets carried by said disk and having their poles and projections from the lower face thereof, circuit-controllers for said magnets provided with movable operating-arms, a stationary bar at one side of said trough provided with cam portions for engaging said operating-arms to cut the magnets out of circuit, and mechanism for imparting a longitudinal reciprocating motion to said trough, substantially as described.

In testimony whereof I affix my signature in the presence of two witnesses.

ALVIN DINGS.
